UNITED STATES PATENT OFFICE.

CHARLS LEOPOLD STOHS AND GUSTAVE R. FUNKE, OF MILWAUKEE, WISCONSIN.

FLUID-RECEPTACLE.

1,226,024.

Specification of Letters Patent. Patented May 15, 1917.

Application filed May 29, 1916. Serial No. 100,552.

To all whom it may concern:

Be it known that we, CHARLS LEOPOLD STOHS and GUSTAVE R. FUNKE, citizens of the United States, residing at the city of Milwaukee, county of Milwaukee, and State of Wisconsin, have invented new and useful Improvements in Fluid-Receptacles, of which the following is a specification.

Our invention relates to improvements in fluid receptacles, and it pertains to that class which are formed of a single piece of fibrous material, (paper, cardboard or the like) so creased that the same may be shipped to the consumer in a compact form in flat unfolded sheets, whereby the material for a large number of receptacles may be packed, shipped and stored in small space, and any one of said sheets readily refolded by an experienced user into the desired shape for storing or shipping milk or the like.

The construction of our invention is explained by reference to the accompanying drawings, in which—

Figure 1 represents one of the sheets, the dotted lines of which indicate the creases at which the same is adapted to be folded to form the receptacle.

Fig. 2 is a plan view of our device as it appears during the process of folding.

Fig. 3 is a perspective view of our receptacle as it appears when completely folded.

Fig. 4 represents a perspective view of our device, the front wall being removed to disclose the interior, and

Fig. 5 is a central vertical section of a completed receptacle.

Like parts are referred to by the same reference numerals throughout the several views.

1 represents a sheet of fibrous material (paper, cardboard or the like) which, as shown in Fig. 1, has been folded and heavily creased upon the dotted lines 2, 3', 4', 5', 6', 7', 8', 9', 10', 11', 12', 13', 14', 15', 16' and 17', whereby the same is readily folded, as stated, by the user preparatory to forming the same into a fluid receptacle, when the aperture 3 is formed therein. 4 is a metallic bottom, provided with angular bends or flanges 5 and 6, by which flanges it is permanently secured to the vertical walls of the receptacle. The clamping flanges 5 and 6 serve to retain the receptacle in its folded

shape, as shown in Fig. 5. The aperture 3 is adapted to be closed by the cap or cover 8 in the ordinary manner. The side walls of the receptacles thus formed comprise five sheets 9, three sheets 10 at their centers and one sheet 11 at their upper ends, while the inner sheet extends down to the bottom of 60 said receptacle, whereby the interior thereof has a plane unbroken surface.

When the bottom member 4 is secured in place the clamping members 5 and 6 are subjected to a heavy pressure, whereby they 65 are forced toward each other and against the opposing surface of the paper or cardboard, thereby forming a liquid tight joint between such parts. A liquid tight joint is also formed between said cap or cover 8 and the upper end of said receptacle, whereby the contents of said receptacle is securely retained therein. The receptacle when complete is preferably submerged in an adhesive liquid, whereby the parts of the material of 75 which such receptacle is formed becomes impervious to liquid.

Having thus described our invention what we claim as new and desire to secure by Letters Patent, is—

1. In a device of the described class, a receptacle formed of a single sheet of fibrous material, which sheet has been previously creased preparatory to being folded into the desired shape, a metallic bottom member 85 provided with an angular groove, the vertical sides of which are rigidly clamped to two opposing sides of the vertical walls of said receptacle, an aperture formed in the opposite end of said receptacle from said 90 metallic bottom, and a cap adapted to close said aperture, said receptacle when formed comprising at its lower end a plurality of thicknesses of material, at its upper end a single thickness of material, and a plurality 95 of thicknesses of material at intermediate points between its respective ends.

2. In a device of the described class, a receptacle formed of a single sheet of fibrous material, which sheet has been previously 100 creased preparatory to being folded into the desired shape, a metallic bottom member provided with an angular groove, the vertical sides of which are rigidly clamped to two opposing sides of the vertical walls of 105 said receptacle, an aperture formed in the

opposite end of said receptacle from said metallic bottom, and a cap adapted to close said aperture, said receptacle when formed comprising at its lower end five thicknesses 5 of material, at its center three sheets, and at its upper end one thickness, substantially as and for the purpose specified.

In testimony whereof we affix our signatures in the presence of two witnesses.

C. LEOPOLD STOHS.
GUSTAVE R. FUNKE.
